The Cincinnati Iron Fence Company-Save-a-
Sink, Cincinnati, Ohio, a joint enterprise

Application February 17, 1947, Serial No. 136,948

Term of patent 14 years

(Cl. D4—2)

To all whom it may concern:

Be it known that I, Donald G. Jensen, a citizen of the United States of America, residing at Cincinnati, in the county of Hamilton and State of Ohio, have invented a new, original, and ornamental Design for Combined Portable Drainboard, Serving Tray and Cooling Rack, of which the following is a specification, reference being had to the accompanying drawing, forming a part thereof, in which

Fig. 1 is a view in perspective of a combined portable drainboard, serving tray and cooling rack, showing my new design when used as a drainboard or serving tray;

Fig. 2 is a plan view thereof;

Fig. 3 is a vertical side sectional view, partly in elevation, taken substantially on the line 3—3 of Fig. 2; and

Fig. 4 is a vertical front sectional view, partly in elevation, taken substantially on the line 4—4 of Fig. 2; and

Fig. 5 is a view in perspective of the device in inverted position when used as a cooling rack.

I claim:

The ornamental design for a combined portable drainboard, serving tray, and cooling rack, substantially as shown and described.

DONALD G. JENSEN.
